FIG. 2

INVENTOR

Charles Ziegler
BY Munro & Co.
ATTORNEYS

UNITED STATES PATENT OFFICE.

CHARLES ZIEGLER, OF LIMOGES, FRANCE, ASSIGNOR TO THE J. POUYAT COMPANY, OF NEW YORK, N. Y., A CORPORATION OF NEW YORK.

DESIGN FOR A COVERED DISH OR SIMILAR ARTICLE.

40,508.

Specification for Design.

Patented Feb. 15, 1910.

Application filed October 25, 1909. Serial No. 524,582. Term of patent 7 years.

To all whom it may concern:

Be it known that I, CHARLES ZIEGLER, a citizen of France, and a resident of Limoges, France, have invented a new, original, and ornamental Design for a Covered Dish or Similar Article, of which the following is a specification, reference being had to the accompanying drawings, forming part thereof.

Figure 1 is a perspective view of a covered dish or similar article, showing my design; and Fig. 2 is a plan view of the same.

I claim:

The ornamental design for a covered dish or similar article, as shown.

CHARLES ZIEGLER.
